GAME APPARATUS

Application filed February 2, 1928. Serial No. 251,250.

This invention relates to game apparatus and is concerned more particularly with an apparatus for playing a game in many respects resembling the game of golf.

5 The winner in a golf match is decided either on the basis of individual holes won, known as match play, or on the basis of the total number of strokes for the round, referred to as medal play, but in either case the number 10 of strokes used on each hole is the determining factor. Similarly, the excellence of the play of an individual is determined by comparison of his stroke total with par, which is an arbitrary score representing 15 theoretically perfect scores for each of the holes, determined in each instance by the length of the hole.

The game of this invention follows the scoring system used in golf and either match 20 or medal play may be employed. As in golf, the players play in turn and at each turn one player manipulates the apparatus to determine his stroke total for the hole being played, the apparatus either directing that the hole 25 has been made in par or in a given number of strokes over or under par. Before the game commences, each player is provided with the usual golf score card which bears the numbers of the holes of the course on 30 which play is considered to take place, together with par for each hole and a space in which the stroke total may be set down.

After his turn, the player then puts down the total for the hole as determined by the apparatus in the space corresponding to that 35 hole. For example, par for the hole being played may be 4 and the apparatus may indicate that the player has taken one stroke over par on the hole. In that event, the player 40 sets down 5 in the space provided as his score. When each of the players has played the desired number of holes, comparison of the score cards is made and the winner is decided on whatever basis is being used. 45 Since at each turn at the apparatus a player ascertains his stroke total for a hole, play proceeds rapidly and any desired number of players may use the apparatus to play an ordinary round of 18 holes in a brief period 50 of time.

In its preferred form, the apparatus includes a chart on which appears indicia, designated "Par", or factors which represent a variation from par. With this chart is associated a member which is set in motion by 55 the player and comes to rest at random, in which position it selects one of the indicia for the player and thus on reference to the score card, the player may determine the number of strokes which he has taken on the hole 60 being played. Preferably, the chart is of circular form and provided with radial lines which define segments, each of which bears one of the indicia. The member may then conveniently take the form of a needle pivoted at the center of the chart and capable of being spun on its pivot by the player to come to rest over one of the segments of the chart. The inscription on the segment thus determined sets forth the stroke total of the player 70 and the segments may be also suitably inscribed to indicate how strokes have been lost by reason of penalties, hazards, etc.

For a better understanding of the invention, reference may be had to the accompanying drawings, in which

Fig. 1 is a sectional view through the preferred form of the apparatus;

Fig. 2 is a plan view; and

Figs. 3 and 4 are sectional and fragmentary 80 plan views respectively of a modified form of the apparatus.

Referring to the drawings, the apparatus is illustrated as consisting of a chart 10 which may be conveniently inscribed on the face of 85 a disc 11, the periphery of which may be provided with an upstanding flange 12 with a turned in edge 13. The disc may, if desired, be made of sheet metal. The chart includes a plurality of segments printed or otherwise 90 inscribed on the face of the disc, these segments bearing suitable indicia designating the manner in which a hole has been played and the number of strokes taken. Preferably there are 18 segments constituting the chart 95 and certain of the segments are designated "Par", while the remaining segments are designated as varying numbers of strokes under or over par. The segments may accordingly be said to bear factors representing varia- 100

tions from par, the inscription "Par" on certain segments as that marked 14, representing a zero variation. Each of the segments, such as that designated 15, and carrying an inscription "One over par," also bears an explanation as to how the extra stroke was taken, as for example, "In the rough".

Pivotaly mounted at the center of the disc is a spinner 16, consisting of a long and 10 short needle 17, 18 respectively, these needles having heads of different sizes so that the spinner is in proper balance. One or the other of the needles is selected by the players before the game is started as being the one 15 to designate the controlling indicia.

In starting the game, each player is provided with a score card of standard type, which may be one used on some golf course with which the players are familiar, or else 20 may be arbitrarily selected. Each player then takes his turn at the apparatus and spins the spinner on its pivot. After a few turns the spinner comes to rest and the needle which has been selected as controlling then selects 25 the segment which determines the player's score for the hole being played. For example, if the hole in question is par 4, then a player using the long needle of the apparatus as shown in Fig. 2, will have a score for the 30 hole of 7, as the segment selected bears the inscription "3 over par". The explanation of the score is stated on the segment to be due to the fact that the player's ball was in a lake and in a trap. If the short needle were 35 the one controlling, the player would have a par stroke for the hole, the designation "Par" on the segment indicating that the player's score has not varied from the theoretically perfect score for the hole.

40 The players take turns at the apparatus and in a round of 18 holes, each player operates the apparatus 18 times. As each operation consumes only a few seconds the game may be played simultaneously by a number of 45 players and an 18 hole round takes only a short time. After the round is completed, scores are compared and the winner determined in the usual manner employed, depending on whether match or medal play has been 50 chosen.

In a modified form of the apparatus shown in Figs. 3 and 4, a circular base member 19 is employed having a downwardly sloping top wall 20 on which may be placed the chart 10. 55 This base member may be made of a block of wood or any convenient material. It is illustrated as made of sheet metal and the overhanging top wall 20 is cut away to leave a central opening 21 into which projects an up- 60 right pin 22 attached to the base member. Mounted on a sleeve 23 which is freely movable on the upper end of the pin is a disc 24 which has a generally conical top surface. The disc 24 has a diameter slightly less than 65 that of the opening 21, so that the disc is free-

ly movable on the pin, and the periphery of the disc is in substantially the plane of the inner edge of the wall 20.

The disc is provided with a groove 25 near its periphery which is formed with a series 70 of spaced depressions 26 and a ball or marble is used as the indicating means. There are as many depressions 26 as there are segments in the chart and when a player is to 75 take his turn, he places the ball in the groove and gives the disc a spin. The ball rolls clear of the groove and may run up the surface of the disc or of the wall 20, eventually dropping into a depression 26 and coming to rest 80 with the disc opposite a segment on the chart thus determining the player's stroke total for the hole.

In some instances, I may prefer to place the chart 10 on the surface of the disc 24, instead of on the wall 20, the segments on the disc 85 which would then bear the indicia of the chart being indicated by the lines 27. The use of the apparatus in this form is as before described.

It will be seen that the game apparatus of this invention is of simple construction and it affords means for playing a game which approaches the game of golf closely, in that the same scoring system is employed. The 18 segments of the chart may bear varying inscriptions as desired, but the chart illustrated 95 contains 9 segments designated "Par" and the remaining segments represent variations from par. It has been found by experiment that a chart so made up will produce a score closely approximating the score of a player of 100 average skill, but a chart having a greater or less number of segments designated "Par" may be employed by players whose skill is greater or less than the average. Preferably a chart will be used which produces scores 105 approximating those of the players and for this purpose separate charts may be employed which can be placed on the face of the disc under the spinner, the chart selected being determined by the average golf score of the 110 players who are to use the game.

What I claim:—

A golf game apparatus which comprises a chart having a portion subdivided to form a plurality of spaces bearing a series of indicia representing par and variations from par, and a member having a portion movable over the chart by the player and coming to rest at random and designating by its position one of said spaces, the indicia-bearing space 115 designated by the member in its position of rest determining whether the player's score on the hole being played is par or a variation therefrom.

In testimony whereof I affix my signature. 125
